[57] CLAIM

The ornamental design for a plastic insert for examining table stirrup, as shown and described.

DESCRIPTION

FIG. 1 is a top plan view of a plastic insert for examining table stirrup, showing my new design;

FIG. 2 is an elevational view of one side of the insert, the opposite side being in mirror symmetry;

FIG. 3 is a bottom plan view;

FIG. 4 is a front end elevational view; and,

FIG. 5 is a view from the opposite end of FIG. 2.
